C. D. BONSALL

CAR ROOF

Filed June 23, 1927

UNITED STATES PATENT OFFICE.

CHARLES DAVID BONSALL, OF PITTSBURGH, PENNSYLVANIA, ASSIGNOR TO P. H. MURPHY COMPANY, OF NEW KENSINGTON, PENNSYLVANIA, A CORPORATION OF PENNSYLVANIA.

CAR ROOF.

Application filed June 23, 1927. Serial No. 200,825.

This invention relates to car roofs and more particularly to single-course roofs of the all-steel riveted-up type wherein self-supporting sheets extend from side plate to side plate of the car and are rigidly secured thereto and to each other to form a rigid load sustaining structure.

The principal object of the present invention is to provide an improved eaves construction for the above type of roof that will secure effective ventilation of the car without affecting the weatherproofing qualities thereof. Other objects are cheapness and simplicity of construction, and ease of assembly. The invention consists principally in the improved eaves construction hereinafter shown and described; and it also consists in the parts and in the combinations and arrangements of parts hereinafter described and claimed.

In the accompanying drawing, which forms part of this specification, and wherein like symbols refer to like parts wherever they occur:

Fig. 1 is a plan view of the eaves portions of a car roof embodying my invention;

Fig. 2 is an enlarged side elevation of the eaves portion of the car, showing one of the ventilating openings and the guard plate therefor;

Fig. 3 is a vertical section on the line 3—3 in Fig. 2; and

Fig. 4 is a perspective view of one of the guard plates.

Referring to the accompanying drawing, my invention is shown in connection with an all-steel, riveted-up, single-course car roof comprising self-supporting roof sheets 5, which extend from eaves to eaves of the car and slope downwardly on opposite sides of the ridge to form a pitch or arcuate roof. As shown in the drawing, the roof sheets are supported at their eaves ends on Z-bar side plates 6, which are arranged with their webs horizontal and with their inner flanges extending upwardly, and are provided with depending eaves flanges 7 that overhang the upstanding inner flanges of said side plates and are secured to the outer faces of such flanges by horizontal rivets 8. The roof sheets are provided with upstanding side marginal seam flanges 9; and metal seam covers 10 of substantially inverted U-shaped

cross-section are placed astraddle adjacent seams flanges and are rigidly secured thereto by horizontal rivets 11, thus constituting outside carlines for the roof. The seam covers 10 extend from eaves to eaves of the car and are provided at the lower edges of their side walls with outstanding base flanges 12 that rest on the body portions of adjacent roof sheets and are turned down at the eaves over the depending eaves flanges 7 of said sheets. As shown in the drawing, the seam covers 10 are of greater depth at the ridge than at the eaves, and their base flanges 12 are wider at the eaves than at the ridge.

In order to prevent rusting of the sheets and damage to the lading due to the sweating or collection of moisture on the undersides of the metal roof sheets, vertically extending, downwardly opening ventilating flues or passageways 13 are provided at the eaves of the car. Said ventilating passageways are formed by hollow outstanding ribs 14 pressed in the depending eaves flanges 7 of the sheets, preferably at points substantially midway of the eaves ends thereof. By this arrangement the middle portions of the depending eaves flanges are spaced away from the outer face of the upstanding inner flange of the side plates far enough to form the ventilating passageways 13, which permit fresh air to pass into the interior of the car between the undersides of the roof sheets and the upper edge of said side plate.

In order to prevent rain, snow, cinders, or sparks from entering the car through the ventilating passageways 13 formed by the outstanding vertical ribs 14 in the depending eaves flanges 7 of the roof sheets, each rib 14 is provided with a metal cover or guard plate 15. Each of the cover plates 15 is provided with a hollow rib 16 adapted to straddle the rib 14 in the depending eaves flange of a roof sheet, and side marginal flanges 17, which are secured to the said eaves flange on opposite sides of rib thereon by horizontal rivets 8, which secure said flange to the upper flange of the side plate. Said cover plate is also provided with a depending outwardly offset skirt or apron portion 18, which projects below the eaves flange of the sheet far enough to protect and cover the lower end of the ventilating flue or passageway formed by the rib 14.

The hereinbefore described arrangement secures free circulation of fresh air through the interior of the car, thereby preventing sweating of the sheets which causes the sheets to rust and is liable to damage the lading; it also serves to prevent rain, snow, and cinders from blowing into the interior of the car through the ventilating passageways; and it also serves to protect and stiffen the outstanding ribs which form said ventilating passageways.

What I claim is:

1. A car roof comprising roof sheets having depending eaves flanges which overhang the side plates of the car and are provided with hollow outstanding ribs which form ventilating passageways, and means on the depending eaves flanges of said sheets for stiffening and protecting said ribs and for weatherproofing the lower ends thereof.

2. A car roof comprising roof sheets having depending eaves flanges which overhang the side plates of the car and are provided with hollow outstanding ribs which form ventilating passageways, means for stiffening and protecting said ribs, said means comprising a plate secured to the depending eaves flanges of said sheets adjacent to each rib and having a portion adapted to straddle said rib.

3. A car roof comprising roof sheets having depending eaves flanges which overhang the side plates of the car and are provided with hollow outstanding ribs which form ventilating passageways, means for stiffening and protecting the ribs in the depending eaves flanges of said sheets and for weatherproofing the lower ends of said ribs, said means comprising a plate secured to the depending eaves flanges of said sheets adjacent to each rib therein and having a portion

adapted to straddle said rib and a portion extending below the lower end thereof.

4. A car roof comprising roof sheets having depending eaves flanges which overhang the side plates of the car and are provided with hollow outstanding ribs which form ventilating passageways, means for stiffening and protecting the ribs in the depending eaves flanges of said sheets, said means comprising a metal plate secured to the depending eaves flanges of the sheets adjacent to each rib and provided with a hollow rib adapted to snugly embrace the hollow rib in the depending eaves flange.

5. A car roof comprising roof sheets having depending eaves flanges which overhang the side plates of the car and are provided with hollow outstanding ribs which form ventilating passageways, means for stiffening and protecting said ribs and for weatherproofing the lower ends thereof, said means comprising a metal plate secured to the side plate on opposite sides of the hollow rib in the depending eaves flange of the sheets and provided with a hollow rib adapted to snugly embrace the hollow rib in said depending eaves flange and a depending apron portion extending below the lower end of said flange.

6. A cover plate for ventilating eaves construction of the kind described, said cover plate comprising a channel shaped body portion adapted to straddle the ventilating rib of a roof sheet, outstanding marginal flanges at the sides of the rib in said cover plate and a depending apron portion disposed in a plane parallel to said marginal flanges and extending below said last mentioned rib.

Signed at New Kensington, Pa., this 20th day of June, 1927.

CHARLES DAVID BONSALL.
